(57) **CLAIM**

The ornamental design for a water weight bag, as shown and described.

DESCRIPTION

FIG. 1 is a front, left, top perspective view of a water weight bag, showing my new design;

FIG. 2 is a rear, right, bottom perspective view thereof;

FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 3;

FIG. 13 is an enlarged view of detail 13 in FIG. 5;

FIG. 14 is an enlarged view of detail 14 in FIG. 5;

FIG. 15 is an enlarged view of detail 15 in FIG. 7; and,

FIG. 16 is an enlarged view of detail 16 in FIG. 8.

The dashed broken lines in the figures are for the purposes of illustrating portions of the water weight bag and form no part of the claimed design.

The dash-dot-dash broken lines are for notating enlarged views and form no part of the claimed design.
